Primary Examiner — David Muller*Assistant Examiner* — Nathan Johnston(74) *Attorney, Agent, or Firm* — Benesch, Friedlander, Coplan & Aronoff LLP(57) **CLAIM**

What is claimed is the ornamental design for a paper towel holder, as shown and described.

DESCRIPTION

FIG. 1 is a perspective view of a paper towel holder showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The components of the display shown in broken lines illustrate portions of the paper towel holder form no part of the claimed design.
